No. 685,454.

Patented Oct. 29, 1901.

G. I. KING.
BOLSTER.

(Application filed Aug. 22, 1901.)

(No Model.)

UNITED STATES PATENT OFFICE.

GEORGE I. KING, OF DETROIT, MICHIGAN, ASSIGNOR TO AMERICAN CAR & FOUNDRY COMPANY, OF ST. LOUIS, MISSOURI, A CORPORATION OF NEW JERSEY.

BOLSTER.

SPECIFICATION forming part of Letters Patent No. 685,454, dated October 29, 1901.

Application filed August 22, 1901. Serial No. 72,928. (No model.)

To all whom it may concern:

Be it known that I, GEORGE I. KING, a citizen of the United States, residing at the city of Detroit, county of Wayne, and State of Michigan, have invented a certain new and useful improvement in Bolsters, of which the following is a full, clear, and exact description, such as will enable others skilled in the art to which it appertains to make and use the same, reference being had to the accompanying drawings, forming part of this specification, in which—

Figure 1 is a side elevational view of my improved bolster, one end being shown in section. Fig. 2 is a top plan view of the same, partly in horizontal section; and Fig. 3 is an enlarged cross-sectional view on line 3 3, Fig. 2.

This invention relates to a new and useful improvement in bolsters designed especially for use in connection with car-trucks.

One object of this invention is to simplify the construction of bolsters of the character described, enabling the employment of a minimum amount of material for the production 25 of a strong and rigid bolster.

Another object is to use structural and rolled members, whereby the parts are easily assembled and repairs can be quickly and readily made.

30 A further object is to enable the employment of a machine-riveter in the assemblage of the parts, thereby facilitating and reducing the cost of manufacture.

With these objects in view the invention 35 consists in the construction, arrangement, and combination of the several parts, all as will hereinafter be described and afterward pointed out in the claims.

In the drawings I have shown a type of bolster in which commercially-rolled members are employed, the bolster being what is known as a "built-up" structure. The essential or main members of the bolster are preferably bulb angles, which are connected together by 45 a plate, so as to produce a very rigid structure, the said plate carrying the usual center and side bearings. The webs of the bulb angles are provided with the usual column-guides, and under each end of the bolster separate spring-seats may be provided, if desired,

or the springs may be seated directly against the plate.

In the drawings, A indicates a plate the outer edges of which are suitably riveted to the outwardly-presented legs or flanges b of the bulb angles B, the bulbs of angles B being shown, as at b'. On the webs of angles B are arranged column-guides C, which are in the form of castings suitably riveted in position. The plate A and the flanges b and 55 bulbs b' of the angles B are cut away, as at a, b'', and b''', respectively, for the passage of the column, or the column-guides C may be entirely dispensed with, the cut-away portions, above mentioned, in the members of 60 the bolster serving as guides for the columns.

The plate A carries the usual center and side bearings, there being arranged under the plate A at these points to strengthen the bolster filler or stiffening pieces D and D', respectively, which are held in position by rivets passing through said pieces and the webs of the angles B. A suitable opening for the king-pin is of course formed in the main 65 filler-piece D. The supporting-springs may 70 be seated directly against the plate A, or separate seats may be provided therefor, if desired.

It will be noticed with respect to the above construction that it follows generally the form 75 of a channel. The plate and legs of the angles are in compression under load while the bulb portions of the angles are in tension. The vertical webs of the angles serve to a 80 certain extent as plate-girders, and in connection with the plate and stiffening-pieces a very 85 rigid bolster is produced.

I am aware that minor changes in the construction, arrangement, and combination of the several parts of my bolster can be made 90 and substituted for those herein shown and described without in the least departing from the nature and principle of my invention.

Having thus described my invention, what I claim, and desire to secure by Letters Patent, is—

1. In a truck-bolster, the combination with bulb angles, of a plate, and means for connecting said plate to said angles, substantially as described.

2. In a truck-bolster, the combination with bulb angles, of a plate, means for connecting said angles and plate, and column-guides arranged on said angles and at the ends of the 5 bolster, substantially as described.
3. In a bolster for car-trucks, the combination with bulb angles, of a plate, means for connecting said plate and angles, column-guides arranged on said angles, and strengthening or filler pieces arranged under said 10 plate and between said angles, substantially as described.
4. The combination with parallel bulb angles having their legs presented outwardly, 15 of a plate riveted to said legs, filler-blocks arranged between and attached to the angles, and center and side bearings, substantially as described.
5. In a bolster, the combination with bulb 20 angles, of a plate, said angles and plate having vertically-alined cut-away portions, and means for securing said plate and angles together, substantially as described.
6. In a bolster, the combination with bulb angles, of a plate, means for connecting said plate and angles, and column-guides on said 25 angles and at the ends of the bolster, said angles and plate having cut-away portions in alinement with said column-guides for the passage of the columns, substantially as de- 30 scribed.
7. In a bolster, the combination with bulb angles, of a plate, means for connecting said plate and angles, column-guides arranged on said angles, said angles and plate having cut- 35 away portions in alinement with said column-guides for the passage of the columns, and filler-blocks arranged between said angles, substantially as described.

In testimony whereof I hereunto affix my 40 signature, in the presence of two witnesses, this 16th day of August, 1901.

GEORGE I. KING.

Witnesses:

GEORGE BAKEWELL,
GALES P. MOORE.
